UNITED STATES PATENT OFFICE.

WILLIAM C. REINMILLER, OF ATLANTA, ILLINOIS.

BURIAL-VAULT.

1,088,725.

Specification of Letters Patent.

Patented Mar. 3, 1914.

Application filed November 28, 1913. Serial No. 803,499.

To all whom it may concern:

Be it known that I, WILLIAM C. REINMILLER, citizen of the United States, residing at Atlanta, in the county of Logan and State of Illinois, have invented certain new and useful Improvements in Burial-Vaults, of which the following is a specification.

My invention relates to an improvement 10 in burial vaults, and the object is to provide a portable vault, which consists of two sections: a base section upon which the casket is supported, and a cover section which is received in the base section.

15 The invention consists of still other novel features of construction and combinations of parts which will be hereinafter more fully described and pointed out in the claim.

In the accompanying drawings: Figure 1 20 is a view in side elevation; and Fig. 2 is a cross sectional view. Fig. 3 is a longitudinal vertical sectional view.

A represents the top of the vault, and B the bottom or tray section.

25 The upper section is adapted to be placed in the bottom of the vault, which would be either of dirt, gravel, or cement. The tray is preferably provided with an elongated opening in the bottom thereof, as indicated 30 at 1, and with side and end flanges 2, 2.

Extending transversely of the tray and from the bottom thereof are a plurality of straps 3, 3. These straps are offset or raised, so that they extend above the bottom of the 35 tray and upon the straps the casket is mounted, so that the casket does not come in contact with the bottom of the grave.

The top of the vault A is preferably made arch-shaped, although the shape of the top 40 is immaterial, and is closed at both ends.

Formed at the bottom along the sides and ends of the top are flanges 4, 4 for the top to rest upon, and which engage the bottom

of the tray section B. Extending about the body are ribs or reinforcing members 5, 5.

45 The flanges 2 of the bottom of the tray B extend above the bottom flanges 4 of the top, so that the two members are connected together, and there is no danger of one being displaced from the other. Furthermore, if 50 desired, the top member can be covered with cement, and the reinforcing members 5 will cause the cement to be held upon the top. The cement entering between the flanges 2 and the top 3 will cause the two 55 members to be connected together.

Handles 6, 6 are formed on the top member, so that it can be lowered into the base member after the casket has been placed in position upon straps or supports 3.

60 The supporting of the casket upon the straps 3 prevents the water from rising inside of the top of the cover, as the air within the cover will prevent the water from rising above the level of the tray, that is, the 65 air inside of the top will keep the water from rising up over the coffin or casket, as the top is air-tight.

I claim:

A burial vault comprising a top and bottom section, the bottom section provided with an open bottom, and flanges formed on the sides and ends thereof, straps spanning the opening of the bottom section upon which the casket is supported, said top section adapted to be received on the bottom section and within the flanges which prevent longitudinal and lateral movement of the top member.

70 75 80 In testimony whereof I affix my signature, in the presence of two witnesses.

WILLIAM C. REINMILLER.
